UNITED STATES PATENT OFFICE.

WILLIAM E. RIDER, OF MANSFIELD, MASSACHUSETTS.

GRATE.

1,205,664.

Specification of Letters Patent. Patented Nov. 21, 1916.

Application filed February 27, 1911. Serial No. 611,210.

To all whom it may concern:

Be it known that I, WILLIAM E. RIDER, of Mansfield, in the county of Bristol and State of Massachusetts, have invented a new and useful Grate, of which the following is a specification.

I have observed that in grate constructions heretofore the clinkers collect upon the walls surrounding the fire to such an extent that the edges of the mass of fuel will not have proper combustion and in some cases the agglomeration of material is so great that the combustion of the body of the fire is interfered with. When attempts have been made to remove the material it has been found not only to be a very difficult matter but portions of the walls themselves are removed and the walls become pitted and materially weakened.

The main object of my invention is to overcome these defects which I do by providing a removable wall adjacent to the fuel.

Other objects are to provide an efficient draft and escape for the fuel at the edges of the mass and these objects I attain by providing a grate surface around the fire.

Other features of my invention will be pointed out below.

In the drawings, Figure 1 is a perspective of a grate wall embodying my invention; Fig. 2 is a partial section on line 2—2 of Fig. 1; Fig. 3 is a section showing the several members of the retaining grate surface and the adjacent supporting grate bars; Fig. 4 is an elevation of the supporting plate; Fig. 5 is a side view thereof; Fig. 6 is an elevation of two adjacent supporting plates, these being slightly different from the supporting plate shown in Fig. 4; Figs. 7, 8 and 9 show modified forms of the retaining grate surface; Fig. 10 is a perspective of a portion of the upper retaining member; Fig. 11 is a perspective of a portion of the intermediate retaining member; Fig. 12 is a perspective of a portion of the lower retaining member; Fig. 13 is an elevation of a modified form of supporting posts; Fig. 14 is a section thereof on line 14—14 of Fig. 13; Fig. 15 is a section of one of said modified posts; and Fig. 16 is a perspective of a modified form of lower retaining member.

Wall A of firebrick is shown in part but

may extend around both sides and back of the fuel supporting grate indicated at B. The wall is recessed but has projecting supporting portions D and D'. Mounted on D and D' are metal plates E each of which has two portions e e projecting from its side with lugs e' e' at the end thereof at right angles thereto forming hooks. These portions e e enter recesses in the wall and are held to it by placing bricks in position in front of said lugs. Each plate also has a horizontal lug e² projecting from its face and also a vertical central lug e³ and lugs e⁴ e⁴ at an acute angle with the horizontal as well as supporting lugs e⁵ e⁵ and spacing lugs e⁶ at the rear. Each plate is also cut away at e⁷ for a purpose to be presently described. These supporting plates rest on the firebrick portions D and D' in Fig. 1 but in Figs. 13, 14 and 15 I show cast metal posts D² D³ and D⁴, D² and D³ being at the center of the wall and D⁴ being at the end, these members being rounded to facilitate cleaning of the ash pit. The posts may be held to the wall in any suitable way and the posts D² and D³ may be bolted together.

The fuel supporting grate bars B which support the fuel are adjacent to the retaining grate surface which retains the fuel on the supporting bars and which in the drawings comprises upper member F, intermediate members G G and lower member H.

Upper member F, preferably of metal, comprises web f and lugs f' f', the top of the lugs being horizontal and the sides of the lugs forming a vertical fuel retaining surface the web f being at an obtuse angle to said vertical surface. The lug f² at the end of member F has a horizontal projection to rest upon a lug of the supporting plate as more fully hereinafter described. Intermediate member G comprises web g which tapers slightly toward the rear and spacing lugs g' whose tops are parallel with the web.

Lower member H comprises vertical retaining surface h having perforations h', two parallel webs h² h² at an acute angle with the retaining surface and spacing lugs h³ h³ whose tops are parallel with the webs. Any desired form of openings or perforations may be had in place of those I have shown and in place of member H I may use member K shown in Fig. 16 in which there

is a single web k and in which the portions k' act as spacing lugs.

In assembling the parts I place member F in position beneath portion L of the wall and the tops of lugs f' support the wall. Member F is supported by plate E by means of the engagement of end lugs f^2 (only one being shown) with lugs e^2 of member E. I then place member H in position where it is held against turning and against movement toward the wall by lugs e^4 e^4 it being clear that the weight of the member will prevent its movement toward the fire. I then insert members G G which fit in the opening e^1 and whose movement toward the wall is limited by the vertical central lug e^3 . I have shown two members G but any desired number may be used. The several members F, G and H form a retaining surface for the side of the fuel and as it is desirable to allow easy descent of the ashes and free circulation of air I use the lugs described to space the webs of the various members, it being clear that there is such a space above web f and between the several webs all of which slopes downwardly away from the fire. It will also be noted that I provide an air space M at the rear of the several members and by using lugs e^5 I space the central supporting members E with relation to each other.

The several members forming the retaining grate surface being preferably of iron are preferably placed in position fairly loosely to allow for expansion of the parts.

With my iron construction of bars the clinkers will not form thereon and yet the iron will not melt because of my provision for full circulation of air. When the retaining surface is to be removed or repaired the members G G are slid upwardly away from the wall and then the other members are removed from position.

It may be desirable to have the lower portion of the retaining grate surface farther from the wall than the upper portion and in that case I may construct the grate surface obliquely as shown in Fig. 9 or convex as in Fig. 7 or concave as in Fig. 8.

It will be clear that my grate has the important advantage of providing proper combustion for all portions of the fuel and that consequently the waste of fuel is much decreased; that the time and labor required for renewing or repairing is much reduced and that the structure is simple and cheaply made. It will also be clear that I have in reality a retaining grate surface that is adjustable to any desired height of fire, and this is because I may use any desired number of intermediate bars without in any way modifying the structure of the other members of the grate surface.

I do not claim the retaining grate elements as such nor the supporting plate as

such nor the downwardly and inwardly extending retaining surface as such in this application as I intend to make those features the subject of another or other applications.

What I claim is:

1. A device of the character described comprising a wall; a fuel support; and adjacent to it fuel retaining means consisting of a member with a horizontal wall-supporting portion, a vertical fuel retaining portion, and a web at an obtuse angle with said vertical portion, a second member with a fuel retaining portion and a web parallel with the web of the first member and having spacing lugs on the upper side of said web, and between said members one or more additional members each having a web parallel with said webs and spacing lugs on the upper side thereof; and means to hold said members removably in place. 70 75 80

2. In a grate the combination of fuel supporting means; a wall adjacent to said supporting means and having a recess; a supporting member secured to said wall within said recess and having a projecting lug; a metal member consisting of a web at an angle with said wall and having on its upper surface lugs whose top surfaces are horizontal, the end lug having a lip to engage the projecting lug of the supporting member, the latter supporting the metal member and the metal member supporting the wall. 90 95

3. A device of the character described comprising a wall with a recess; a fuel support; and fuel retaining means comprising a member with a horizontal wall supporting portion, a vertical fuel retaining portion and a web at an obtuse angle to said vertical portion and comprising also another member within said recess with two webs parallel with the web of the first member and having vertical fuel retaining means between said two webs, said two members being spaced apart. 100 105 110

4. A device of the character described comprising a wall with a recess; a fuel support; and fuel retaining means comprising a member with a horizontal wall-supporting portion, a vertical fuel retaining portion and a web at an obtuse angle with said vertical portion and comprising also a member having a web parallel with the web of the first member, the said members being spaced apart. 115 120

5. A furnace comprising a wall; a fuel support; and adjacent to the fuel support a fuel retaining surface consisting of a member with a horizontal wall-supporting portion, a vertical fuel retaining portion, and a web at an obtuse angle with said vertical portion; a second member with a fuel retaining portion and a web parallel with the web of the first member; and between said members one or more additional members each 125 130

- having a web parallel with said webs, said members being spaced apart; and means to hold said members removably in place.
6. A device of the character described comprising a wall with a recess; a fuel retaining means within said recess and comprising a plurality of removable members coöoperating to hold each other in said recess to support said wall.
7. A device of the character described comprising a fuel supporting portion; a wall; and a supporting member having a fuel retaining portion, said member consisting of a plate having a portion projecting from its side and having a lug at its end, said plate having also projecting from its face a lug at an acute angle with the horizontal, said first-mentioned lug engaging said wall; and a fuel retaining grate bar having a vertical portion adjacent to the fire, said bar having a web at an angle with said vertical portion, said web resting upon said second-mentioned lug.
8. A device of the character described comprising a fuel supporting portion; a wall; and a supporting plate having a vertical body portion; a hooked projection at one edge of the body portion to engage said wall, a vertical central lug, and a lug projecting from its face at an acute angle with the horizontal; a fuel retaining member having a vertical portion adjacent to the fuel and limited in its movement away from the fire by said vertical lug; and a fuel retaining member having a vertical portion adjacent to the fire and a web at an angle with said vertical portion, said web resting upon the said projecting lug.
9. A device of the character described comprising a fuel supporting portion; a wall; a supporting plate having a vertical body portion, a hooked projection at one edge of the body portion to engage said wall, a vertical central lug and a lug projecting from its face at an acute angle with the horizontal, the central portion of the plate being cut away at one side; a fuel retaining member having a vertical portion adjacent to the fuel and resting in said cut-away portion and being prevented from movement away from the fire by said vertical central lug; and a fuel retaining member having a vertical portion adjacent to the fire and a web at an angle with said vertical portion, said web resting upon the said projecting lug.
10. A device of the character described comprising a fuel supporting portion; a wall; and a supporting plate having projections on its front face and a lug on its rear face to space said plate from said wall; and fuel retaining grate bars supported by the projections on said front face.
11. A device of the character described comprising a fuel supporting portion; a wall; and a supporting member consisting of a portion to engage said wall and being cut away opposite said portion; and a fuel retaining member removably supported by said supporting member movement of which in a direction away from the fire is prevented by the edge of the cut away portion of said supporting member.
